UNITED STATES PATENT OFFICE.

WALTER BAUCHWITZ, OF LEIPZIG, GERMANY.

MACHINE FOR PUNCHING AND AFFIXING CHARACTERS AND THE LIKE OF PAPER.

1,194,268.

Specification of Letters Patent.

Patented Aug. 8, 1916.

Application filed March 28, 1914. Serial No. 828,054.

To all whom it may concern:

Be it known that I, WALTER BAUCHWITZ, a citizen of the German Empire, residing at Leipzig, in Germany, have invented certain new and useful Improvements in Machines for Punching and Affixing Characters and the like of Paper, of which the following is a specification.

The object of this invention is to provide a simple and inexpensive manually operated apparatus for punching characters and the like out of paper and at the same time affixing them to a backing of cardboard without the use of an adhesive, the apparatus being thus suitable for the production of show-cards, advertisements and the like, which can be prepared without skilled labor by the persons having occasion to use the same.

Two embodiments of the invention are shown in the accompanying drawings, in Figures 1 to 4 and Fig. 5 respectively.

Fig. 1 is a sectional elevation, and Fig. 2 an elevation showing the operative parts in a different position. Fig. 3 is an end view of the machine, and Fig. 4 a plan view. Fig. 5 is a side elevation, partly broken away.

Referring in the first instance to the construction shown in Figs. 1 to 4, *a* designates a flanged foot supporting one end of a bed plate *b*, the opposite end of the latter being supported by a foot *j*. On the bed plate *b* there is a sliding plate or carriage *c*, which serves as an anvil and has side plates or flanges *d* whereby it is engaged with the bed plate. These plates *d* are not rigidly fixed to the anvil, but the shanks of studs *e* on the anvil pass through vertical slots *f* in the plates *d*, so that the latter have limited vertical movement, the plates *d* being retained in connection with the anvil by the heads *e* of the studs. The bottom edges of the plates *d* are in part inclined, as shown at *d*', and to the sides of the bed plate *b* are fixed wedge shaped abutments *g* arranged so that by co-action with the said inclined parts they lift the plates *d* when the anvil is moved to the position shown in Fig. 2. The plates *d* support, near their upper edges, the punch *h* or a set of punches. For this purpose they have horizontal slots *d*², in which rest the ends of horizontal cross bars *i* having collars *k* abutting against the inner faces of the plates *d*. On to the ends of the cross bars *i*, which project through the slots *d*², are screwed nuts *m*. By tightening up

the latter the cross bars can be fixed in selected positions in the slots *d*². When they have been adjusted and fixed the punch *h* is placed thereon. In the example illustrated there are four cross bars, adapted to support two punches. When the anvil *c* is in the position shown in Fig. 2, the punch is raised by the plates *d* so that a sheet of card-board *x* and a sheet of paper *y* lying on said card-board can conveniently be laid on the anvil under the punch. The anvil has a handle *c*', whereby it can be pushed under a press plate *n* supported above the opposite end of the bed. When the anvil is so moved the plates *d*, with the punch, drop into a position in which the punch rests on the paper and card-board and holds the same firmly on the anvil, the punch itself lying evenly under the press plate *n*. The latter has a shank *n*', whereby it is vertically guided in a yoke *q*. The press plate is depressed by means of a cam *p* actuated by a crank *o*. By fitting a tubular extension to the latter a large leverage may be obtained, enabling very high pressure to be applied to the punch. By depression of the press plate the punch is caused to cut a character out of the sheet of paper, and at the same time firmly impress the same into the sheet of cardboard.

In Fig. 5 *b*' designates a bed plate, supporting a sliding anvil *c*², with a handle *c*²', similar to that described with reference to Figs. 1 to 4. The movable side plates, designated *d*², whereby the die is supported, are, however, provided with inclined slots *d*³, engaged with abutments *s* projecting from the sides of the bed plate. These abutments *s* serve to pull the plates *d*² downward when the anvil is moved toward the press. The press is broken away in Fig. 5.

The operation of the machine will be readily understood from the above description of the parts. In order to produce a show-card or advertisement the anvil is drawn into the position in which it is shown in Fig. 2, and punches for cutting out the characters required are placed upon the raised punch holders of the plates or flanges *d*. Then a piece of card-board is laid upon the surface of the anvil under the punches, and on this card-board a sheet of paper of a different color. The anvil is then pushed under the press, this movement causing the punches to drop onto the surface of the paper. The press is then actuated, so that the

punches are caused to cut the characters out of the paper, at the same time making slight depressions in the surface of the cardboard, in which the characters remain firmly fixed. The anvil is then withdrawn, the punches being at the same time automatically raised, so that the cardboard and paper can be taken off the anvil. The sheet of paper out of which the characters have been cut can then be removed from the cardboard, and the show-card or advertisement is ready for use.

What I claim as my invention and desire to secure by Letters Patent of the United States is:—

1. In a machine for the purpose set forth the combination of a press, a bed, a manually reciprocatable anvil movable on said bed to and from said press, a movable punch support carried by said anvil, and means whereby said punch support is automatically raised from said anvil by the movement of the latter from said press.
2. In a machine for the purpose set forth the combination of a press, a bed, a manually reciprocatable anvil movable on said bed to and from said press, a movable punch support carried by said anvil, and abutments fixed to said bed whereby said punch support is automatically raised from said anvil in the course of the movement of the latter from said press.

3. In a machine for the purpose set forth the combination of a press, a bed, a manually reciprocatable anvil movable on said bed to and from said press, a movable punch support carried by said anvil, and abutments fixed to said bed, whereby said punch support is automatically raised and lowered on said anvil in the course of the movements of the latter from and to said press respectively.

4. In a machine for the purpose set forth the combination of a press, a bed, a manually reciprocatable anvil movable on said bed to and from said press, vertically movable vertical plates engaged with the sides of said anvil and having horizontal slots above the level of said anvil, cross bars over said anvil extending with their ends through said slots and adapted to support a punch, nuts on the ends of said cross bars, whereby the same are fixable in selected positions in said slots, and abutments fixed to said bed, whereby said vertical plates are automatically raised in the course of movement of said anvil from said press.

In witness whereof I have signed this specification in the presence of two witnesses:

WALTER BAUCHWITZ.
